United States Patent Office.

WILLIAM MELVELL, OF PATERSON, NEW JERSEY.

Letters Patent No. 80,198, dated July 21, 1868.

IMPROVED MACHINE FOR HEADING BOLTS

The Schedule referred to in these Letters Patent and making part of the same.

TO ALL WHOM IT MAY CONCERN:

Be it known that I, WILLIAM MELVELL, of Paterson, in the county of Passaic, and State of New Jersey, have invented a new and improved Bolt and Rivet-Heading Machine; and I do hereby declare that the following is a full, clear, and exact description thereof, which will enable others skilled in the art to make and use the same, reference being had to the accompanying drawings, forming part of this specification.

Figure 1, Sheet I, represents a plan or top view, partly in section, of my improved bolt and rivet-heading machine.

Figure 2, Sheet II, is a vertical transverse section of the same, taken on the plane of the line x x , fig. 1.

Figure 3, Sheet II, is a longitudinal vertical section of the same, taken on the plane of the line y y , fig. 1.

Similar letters of reference indicate corresponding parts.

The invention relates to an improved machine for cutting the blanks and for forming the heads of bolts and rivets, and consists in such an arrangement and combination of dies, holders, punch, and cutter, that the desired result will be attained with simple mechanism and in a short time.

The whole machine operates perfectly automatically, as after the various parts have been adjusted to the production of certain kinds of rivets or bolts, the end of the bar has only to be inserted in the machine, when it will be cut, and the separated blank will be held and headed in the desired manner, as will be hereinafter more fully described.

The punch as well as the dies and holders can be easily removed and replaced, so as to allow the application of the machine to bolts and rivets of various length and shape.

A, in the drawing, represents the frame of my improved bolt and rivet-heading machine. The said frame is made of wood or metal, or of both, and in its rear part are the bearings for a horizontal driving-shaft, B, to which rotary motion is imparted by suitable mechanism.

In front of the driving-shaft are arranged, in an elevated portion of the frame, the bearings for a shaft, C, which is parallel with the driving-shaft, but higher than the same, as shown.

On the shaft C is a cam, a, which operates a sliding block, D, that carries at its lower end a heading-die, E, as shown. Above the shaft C is attached to the frame A, a stationary yoke, b, to which a suitable spring, F, is secured, which serves to raise the block D. Thus, if the shaft C revolves, the cam a depresses the block D and die E, and then the same are raised again by the spring F. The shaft C receives rotary motion by means of gear-wheels, e, or otherwise, from the shaft B, or from any other suitable shaft.

Under the die E is arranged, in the frame A, a stationary die, G, which has a grooved upper surface, the groove being of equal size and form as that in the lower surface of the die E.

In fig. 2, these grooves are represented to be so shaped that a square hole is produced through the whole die, E G, when E is upon G, as in fig. 3. Both dies E G can be easily removed, and replaced by others having different-sized or shaped grooves. They are secured in any suitable manner into their respective holders, but I prefer to dove-tail them into their places, as indicated in fig. 1.

On the shaft B, in line with the grooves in the dies E G, is mounted a cam, d, which serves to move a sliding block, H, toward the said dies, while a spring, e, shown in fig. 3, serves to draw the said block toward the shaft B.

In the block H is held a punch, I, the end of which is so shaped that it will accurately fit the grooves in the aforesaid dies.

During the rotation of the shaft B, the punch is alternately moved forward and backward, being moved forward when the die E is down, and backward when the same is up or is being raised. The punch has a head, f, at or near its rear end, by which it is held in and moved by the block H. It is fitted from the top or side into a groove in the said block, and is therefore easily removable, to be replaced by one of different length, or by one that has a different-shaped end.

In front of the die G are pivoted, with their lower ends to the frame A, and opposite to each other, two

swinging bars, plates, or frames, J J, which have boxes, K K, formed at their upper ends. In these boxes are fitted the blank-holders L L, as shown. By means of springs, g g, the frames J are held apart, as in fig. 2, and the grooved faces of the blank-holders are then also apart.

The boxes K are formed with oblique outer sides, as in fig. 1, and against these oblique sides fit the oblique faces of sliding wedges, M M, that are operated by means of cams, h, on the shaft B. When the wedges are pushed forward by the cams, they swing the frames J J toward each other, so that the faces of the holders L come in contact, as in fig. 1, and the grooves in the said holders then form a hole, which is in line with the hole through the dies E G, and which is of such size that the blank to be headed will be held in it.

The holders can be easily removed from the boxes K, to be replaced by others, which will hold blanks of different length or diameter. When the cams h cease to act upon the wedges, the same are either drawn or forced back by the indirect action of the springs g, or by that of springs i i acting directly upon them, and then the frames J are again swung apart by the springs h.

The frames J may be pivoted at their upper ends to an elevated part of the frame A, in which case the boxes K will be formed at their lower ends. The action of the parts will, in that case, remain similar to that described.

On the front end of one of the holders L is formed, secured, or attached a cutter, N, which, as the holders are forced together by the action of the wedges, sweeps past the front end of the other holder L, and cuts any bar that may be held between the holders.

The main advantage of the swinging holders L L over sliding holders is, that by that motion a drawing cut is produced by the cutter, and less power to operate the cutter is consequently required.

The operation of the machine will, from the above, be sufficiently clear, but I will recapitulate the various motions in the order in which they act upon the blank.

The end of the bar from which the blank is to be made is held upon the die G against the end of the then withdrawn punch I. The bar may be partly supported by an adjustable support, j, as shown in fig. 3.

The holders L L are then simultaneously, with the die E, moved toward the bar, and thereby the front end of the blank is cut off by the cutter. The separated blank is then held by the holders L, and its rear end is within the dies E G.

The punch is then moved forward, and heads that portion of the blank which is within the dies, and then simultaneously the holders and dies are drawn apart, and the punch moved back, so as to release the finished bolt or rivet, which falls off the die G.

The machine is then in position to receive a new blank, and to act upon the same in the aforesaid manner.

By means of suitable stops, one of the frames J can be retained in its upright position, when its box K or holder I can answer for an anvil to shape the ends of bars, or for other purposes.

I claim as new, and desire to secure by Letters Patent—

The improved bolt and rivet-heading machine, consisting of the oscillating-holder L L, carrying the cutter N of the stationary die G and reciprocating die E, and of the reciprocating punch I, all made and arranged substantially as herein shown and described, and combined with the two cam-shafts B and C and springs g, F, and e, respectively, in the manner set forth.

WILLIAM MELVELL.
